DESIGN FOR A DOILY

Edward Karfiol, New York, N. Y.

Application April 26, 1935, Serial No. 56,571

Term of patent 14 years

To whom it may concern:

Be it known that I, Edward Karfiol, a citizen of the United States, residing in New York, in the county of New York and State of New York, have invented a new, original, and ornamental Design for a Doily, of which the following is a specification, reference being made to the accompanying drawing, forming part thereof, in which:

The figure represents a face view of a doily showing my new design. The full lines of the drawing show one-eighth of the design in detail, the other seven-eighths sections, indicated in dotted lines except the border which is shown in full lines, being repetitions of the detailed illustration arranged in proper relation thereto.

I claim:

The ornamental design for a doily as shown and described.

EDWARD KARFIOL.
